UNITED STATES PATENT OFFICE.

PERRY WEST, OF NEWARK, NEW JERSEY, ASSIGNOR, BY MESNE ASSIGNMENTS, TO ELLIOTT COMPANY, OF PITTSBURGH, PENNSYLVANIA, A CORPORATION OF PENNSYLVANIA.

DEACTIVATOR.

Application filed April 28, 1923, Serial No. 635,401. Renewed April 13, 1925.

To all whom it may concern:

Be it known that I, PERRY WEST, citizen of the United States, and resident of Newark, in the county of Essex and State of New Jersey, have invented certain new and useful Improvements in Deactivators, of which the following is a specification.

This invention relates to a device known as a deactivator, or deaerator, which is an apparatus for separating oxygen and other gases from water and other fluids and removing said free dissolved gases, thereby rendering the fluid non-corrosive.

An important object of the invention is the provision of a deactivating apparatus having a fluid-level governor for regulating the intake of fluid to be treated so that a constant level of such fluid may be maintained within the apparatus and providing for and controlling a recirculation of fluid within the apparatus and to maintain a mechanical agitation of such fluid.

Another object of the invention is the provision of automatically operated means adapted to prevent rise of fluid within the apparatus above a predetermined level. Should the fluid rise above such predetermined level, due to leakage or other causes, means are provided to cause excess of fluid within the apparatus to be pumped back into the source of supply, or elsewhere. Said means is also adapted for automatically cutting off the power from the vacuum pump of the apparatus when the fluid level in the tank rises beyond a predetermined point, and for again applying power to said pump when the level of the liquid has been reduced below said predetermined level.

I also provide the separating chamber or tank with means, such as a screen or screens, for breaking up and keeping in suspension the sprayed or atomized fluid to be treated and, in connection therewith, a system of spraying devices for effecting mechanical agitation and breaking up of the fluid to be treated and the introduction of such fluid into a vacuum chamber or tank.

These and other features of the invention not hereinbefore referred to will be herein-after described and claimed and are illustrated in the accompanying drawings, in which—

Figure 1 is a side elevation of an apparatus embodying the invention;

Fig. 2 is an end elevation thereof,

Fig. 3 is a section through the device showing spraying piping and screens, and

Figure 4 is a diagrammatic view illustrating the various connections.

Similar characters designate like parts in all the figures of the drawings.

Referring to the drawings, 1 designates a receptacle or tank of cast-iron or other suitable material adapted to withstand a high vacuum without appreciable leakage of fluid or gases, said receptacle having removable heads 2, with transparent observation panels 3 therein. At 4 I have shown a double wire screen, this screen being adapted to break up or atomize injected fluid and prevent it from being projected directly against the walls of the tank 1, thus keeping the fluid in suspension. Said screen is of fine mesh, is supported on frame work and encircles the upper portion of the tank. An inlet opening for raw fluid is shown at 5, the necessary distributing piping within the tank being designated by 6, 7, 8, 9 and 10, and spraying nozzles for such piping being designated by 11, 12, 13, 14, 15 and 16. Outlet openings 17 and 18 in the tank 1 permit liberated free oxygen or other free gases to be removed from said tank, a pipe line 19, 20, 21, 22, 23 conveying said gases to a separator 25 adapted for separating entrained fluid or other foreign substance therefrom. A vacuum pump 26 or other suitable device is employed for removing liberated gases from the tank 1 and for maintaining in said tank any desired reduced pressure.

A motor 27 or other suitable power device may be employed to operate said pump, the drive connections being shown at 28. A pipe line 29, 30, 31, 32 connects the separator 25 and the pump 26, a check valve 33 and gate valves 34, 35, 36 in pipe line from tank 1, through separator 25 to pump 26 being shown.

The tank 1 also has an outlet 37 for treated fluid, a pipe line 38, 39, 40, 41, 42, 43 leading from said outlet to a removal pump 44 for such treated fluid, a check valve 45 and a gate valve 46 being provided in said pipe line. A delivery pump 47 is connected by pipe line 48, 49, and 51 from discharge of removal pump 44, said pipe line having a gate valve 50 and a check valve 52, permitting conveyance of treated fluid to the point of use, through pipe line 54,

55, 56, 57, 58, provided with check and gate valves 59 and 60.

A re-circulation pipe line 61, 62, 63, leads from the discharge of removal pump 44

6 to the intake piping system within the tank 1, 64 designating a gate valve and 65 a float-operated regulating valve in the line.

Raw, untreated fluid is brought to the opening 5 of the tank 1 by piping 66, 67, 10 a gate valve 72 and a float-operated regulating valve 73 being shown herein.

At 74 there is shown an automatic float-operated fluid level governor for operating the regulating valve 73 through the levers

15 75 and 76 and the link 77, and also for operating the regulating valve 65 through levers 78 and 79 and the link 80. A pipe line 81, 82, 83, connects the top of the float chamber 74 with the top of the tank 1, and

20 another pipe line 85, 86, 87, 90 connects the bottom of the float chamber with the bottom of the tank, a gate valve 91 being shown in the latter pipe line, and a support for the float chamber being shown at 25 92. The removal pump 44 and the delivery pump 47 are operated by a motor or other suitable drive appliance 93, a shaft connection 94, 95, 96, 97, 98, 99 being shown.

100 is an automatic float-operated fluid-level governor operating float-switch control 101, through float-levers 102 and 103, and link 104, and also operating the auxiliary valve 105 through said lever 102 and link 106.

35 A pipe line 107, 108, 109, 110, leads from the discharge of delivery pump 47 to the source of supply, 113 and 114 designating a check valve and gate valve respectively in this line. A pipe line running to waste 40 is designated by 115, 119 and 120 are a gate valve and check valve respectively therein. Another line running to waste is shown at 121, 122, and a gate valve therefor at 124.

A pipe connection from the top of the 45 float chamber 100 to the top of tank 1 is designated by 125, 126, while a pipe connection from the bottom of said float chamber to the bottom of said tank is designated by 129, 130. A gate valve in the latter 50 line is shown at 134. At 135 is shown a support for the float chamber 100. A blow-off and drain in connection to waste from the bottom of the apparatus is shown at 136, and 137 is a gate valve therein.

55 A recording vacuum gauge and a recording pressure gauge are shown herein, the former designated by 138 and having a pipe line 139, 140, 141, 142 connecting with the top of the tank 1 and having a valve 60 143 therein, and the latter being designated by 144 and having a pipe line 145, 146 from the discharge of delivery pump 47, said line having a valve 147 therein.

An automatic starter and control for the 65 motor 27 is shown at 148, and a connection

between the float switch 101 and said control is shown at 149, 150, 151.

The operation of the apparatus is as follows:

The fluid to be treated is brought in 70 through pipe and valves 66, 72, 73, to the intake 5 in the bottom of the tank 1, and thence passes through pipes 6, 7, 8, 9, 10 to the outlets 11, 12, 13, 14, 15 and 16. The fluid being brought into a region of vacuum 75 under a pressure greater than that of the atmosphere a violent agitation and breaking up of said fluid occurs as it leaves the inlet nozzles and is projected upward in the tank 1. The fluid, now in the form of a mist, is projected against the screen 4, which tends to further break up and atomize said fluid and also prevents it from forming in heavy films and running down the sides of the tank 1. This violent 80 agitation results in the breaking up, atomizing and keeping in suspension of the fluid and causes the free dissolved oxygen and other free gases contained therein to be liberated, and permits them to be 85 drawn off by means of the vacuum in the tank. The precipitated fluid falling to the bottom of the tank may be maintained at any predetermined level by means of the 90 automatic fluid-level governor 74.

95 The gases liberated in the manner above described may now be drawn off through the openings 17 and 18 in the tank 1 and through pipe line 19, 20, 21, 22, 23, to the separator 25, where entrained fluid and other foreign matter is extracted. The liberated gases now leave the separator 25 through pipes 30, 31, 32 to the pump 26, from which they are discharged into the atmosphere. The entrained fluid, etc., removed in separator 25 passes by gravity through pipe line 152 and 153 to the tank 1.

100 The fluid-level governor 74 controls the amount of raw fluid admitted to the apparatus and the amount recirculated, to maintain a continuous agitation regardless of the amount of raw fluid handled. Said governor 74 has a float chamber connected by pipe lines to the bottom and the top of the tank 1, the bottom connection permitting the fluid 105 in the tank to pass back and forth in the float chamber, and the top connection being for the purpose of equalizing the pressures in the tank and the float chamber, so that the fluid levels may correspond. Within the float chamber there is a float connecting to levers 75 and 78 by means of a rod and shaft, so that the raising or lowering of the fluid level in the float chamber will by raising or lowering the float raise or lower the 110 levers 75 and 78.

115 When the treated fluid is removed from the tank 1 and delivered away from the apparatus by the pump 47 the level of fluid in said tank will be lowered, thereby lowering 120 125 130

the level of fluid in the governor 74. This will cause the outstanding end of lever 78 to raise, and this in turn will raise the outstanding end of lever 79 by acting through link 80, which will open regulating valve 73. More raw fluid is thus admitted to the tank, raising the fluid level therein. As soon as the raw fluid is admitted at a rate exceeding that at which the treated fluid is withdrawn from said tank, the level of the fluid in the tank 1 will be raised, thereby reversing the action of the governor and closing the regulating valve 73. When the fluid reaches normal level in the tank the valve 73 will be entirely closed, and this automatic operation will continue to maintain the fluid at an approximately constant level. It will be noted that the outstanding end of the lever 75 will be operated in the reverse direction from the outstanding end of the lever 78, and that such operation of lever 75 through link 77 and lever 76 will open regulating valve 65 as regulating valve 73 is being closed, and to close regulating valve 65 as regulating valve 73 is being opened. Turnbuckles are provided on the links 77 and 80, so that any desired relationship may be maintained between the operating mechanism of the regulating valve 65 and the regulating valve 73, the preferred relationship being such that when valve 73 is entirely closed the regulating valve 65 will be opened to the proper extent to permit passage of sufficient recirculated fluid from the removal pump 44 to the inlet of the tank to produce the required agitation of the fluid therein. The relationship between these regulating valves is such that when valve 73 is fully opened the valve 65 will be fully closed, thus preventing passage of any of the fluid being delivered by the removal pump 44 back through the recirculating system into the tank 1, and leaving the full capacity of this pump free to deliver to pump 47 and thence to point of use the treated fluid. The fluid-level governor thus controls the inlet of raw fluid so as to maintain an approximately constant level thereof, and in addition causes a portion of the fluid to recirculate by way of tank 1, pump 44, intake 5 and agitating apparatus back to the tank 1, thus preventing diminution of the agitating process when little or no raw fluid is being taken into the apparatus.

This recirculation has been found highly desirable, particularly with cold water deaeration or deactivation, as the recirculation not only repeatedly subjects the water to the conditions maintained in the tank 1, but also tends to always maintain a condition of agitation in which the water is kept finely divided. While in this divided state the air is much more easily released from the water, thereby enabling a more nearly complete separation and release of the air. The recirc-

culation has the effect, also of increasing the effective tray area due to the repeated use thereof.

The particular arrangement herein shown for recirculation has also been found to be advantageous, as the amount of recirculation is regulable on a basis of the amount of water delivered by the apparatus to its external load. As the delivery to the external load increases, the recirculation decreases, and vice versa, thereby cutting down power consumption on the removal and recirculating pump.

The fluid-lever governor 100, similar to governor 74, is connected to the tank 1 in a similar manner, but is set at a higher level. The governor 100 is adapted to operate an auxiliary valve 105 and also to operate a float-switch 101. As a regulating valve such as 73 may become leaky, either through deterioration of the valve or because of interference of operation by some foreign substance, because of pressure of incoming fluid in connection with reduced pressure in the tank 1, an excessive amount of raw fluid may flow into the tank when valve 73 is supposed to be closed. Under these conditions the level of fluid in the tank may continue to rise above normal level and may entirely fill the tank unless proper means are used to prevent this happening. Also the vacuum pump may be severely damaged by allowing the fluid to pass into the operating chamber of the pump. The governor 100 prevents this by operation in the following manner: The float chamber of this governor is so connected with the tank 1 that a rise of the fluid above normal level will cause a rise in the float chamber, thereby raising the float therein and causing the outstanding end of the lever 102 to be raised. The raising of the lever 102 first causes valve 105 to be opened through the action of the link 106. This opening of the valve 105 allows some of the fluid to pass from the discharge of pump 47 out through 107, 108, 109, 110, back to source of raw fluid supply, thus removing some of the fluid from the apparatus and lowering the fluid level in the tank 1. This removal of fluid from the tank will lower the fluid level so that the float in the governor 100 will again close the valve 105 as soon as the fluid has again reached a proper level, and this action will continue to prevent any substantial rise in the fluid level in the tank above the level in the float chamber 100. If the intake of raw fluid is at a greater rate than can be cared for in this way, the fluid level in tank 1 will continue to rise after the valve 105 is fully opened and in full operation, so that there is still danger that the apparatus may become filled with the fluid and cause damage to the vacuum pump. In such case the further rise of the lever 102 will cause the float-switch 101 to be operated

through the link 104 and the lever 103 so as to cause the motor control 148 to stop the motor 27 driving the vacuum pump 26. This condition will remain until the fluid 5 level in tank 1 is again lowered, when the reverse action of the governor 100 will first cause the float-switch 101 to operate to start the motor 27 and pump 26 and then to close the valve 105. The functions of the 10 governor 100 are therefore to first prevent the raising of the fluid level in the tank 1 above a predetermined height by opening valve 105 and allowing a portion of the fluid to be pumped back from the tank to the source 15 of supply, and, secondly, to automatically stop the pump 26 if the first operation does not prevent undue rise in said tank. The governor 100 thus acts to prevent the raising of the fluid level in the tank 1 above the level 20 of the spraying devices, to prevent improper operation of the apparatus due to interference of too high a fluid level in the fluid tank with the proper agitating of the incoming fluid.

25 The recording vacuum and pressure gauges permit proper regulation and maintenance of pressure within the tank and at the nozzles, and their function is well understood.

It will be understood that the present apparatus embodies coordinate means for maintaining a vacuum in the tank 1, and also for controlling the absolute pressure ratio of the partial pressures due, respectively, to freed gas and the vapor of the liquid. This 30 insures continuous conditions within the tank such that air will be effectively released from the liquid.

On account of the arrangement herein 40 shown and described it is not necessary to heat either the incoming water or the sprayed water in the tank.

What I claim is:

1. A deactivator, embodying a fluid chamber, means for maintaining a vacuum therein, means for spraying a fluid thereinto, a screen within said chamber for further breaking up said fluid, means for removing freed gases from the chamber, means for removing treated fluid therefrom, means for maintaining a constant flow of liquid within the apparatus, and an auxiliary water-line governor adapted to operate upon failure of said first governor.

55 2. A deactivator, embodying a fluid chamber, means for maintaining a vacuum in said chamber, means for spraying a fluid thereinto, a screen within said chamber for further breaking up such fluid, means for removing freed gases from the chamber, means for removing treated fluid therefrom, a recirculation pipe line leading from said fluid removal means to said fluid chamber, and means for preserving a fixed fluid level 60 therein and also for controlling a recirculation of the fluid within the apparatus

through said recirculation pipe line in order to maintain a suitable mechanical agitation both when raw fluid is being admitted and when little or no raw fluid is admitted.

3. A deactivator, embodying a fluid 70 chamber, means for maintaining a vacuum in said chamber, means for spraying a fluid thereinto, a screen within said chamber for further breaking up said fluid, means for removing freed gases from the chamber, 75 means for removing treated fluid therefrom, and an automatic float-operated device for preventing rise of fluid level above a predetermined point to cause a part of the fluid in the apparatus to be pumped back to the source of supply or elsewhere without the apparatus.

4. A deactivator, embodying a fluid chamber, means for maintaining a vacuum in 85 said chamber, means for spraying a fluid thereinto, a screen within said chamber for further breaking up of said fluid, means for removing freed gases from the chamber, means for removing treated fluid therefrom, an automatic float-operated device for preventing the rise of the fluid level above a predetermined point to cause a portion of the fluid in the apparatus to be pumped back to the source of supply or elsewhere without the apparatus, and an auxiliary 90 automatic float-operated device adapted to cut off power of the vacuum maintaining means when the fluid level rises beyond a predetermined point and again applying power to the vacuum maintaining means when 95 said level in the apparatus has been reduced below the predetermined level.

5. A deactivator, embodying a fluid chamber, means for maintaining a vacuum therein, means for spraying a fluid thereinto, 105 means for removing freed gases therefrom, means for removing the treated fluid, a recirculation pipe line leading from said fluid removal means to said fluid chamber, and a float-operated fluid-level governor for 110 maintaining a fixed fluid pressure in the tank and controlling the recirculation of the fluid through said recirculation pipe line.

6. A deactivator, embodying a fluid chamber, means for maintaining a vacuum therein, means for spraying a fluid to be treated thereinto, means for removing the freed gases from the chamber, means for removing treated fluid therefrom, a recirculation pipe line leading from said fluid removal means to said fluid chamber, a float-operated fluid-level governor for maintaining a fixed fluid level in the chamber, said governor 115 also controlling the recirculation of the fluid through said recirculation pipe line, and an auxiliary water-line governor adapted to operate upon failure of said first governor.

7. A deactivator, embodying a fluid chamber, means for spraying a fluid thereinto, 120 means for removing freed gases from the

- chamber, means for removing treated fluid therefrom, a recirculation pipe line leading from said fluid removal means to said fluid chamber, and means for maintaining a fixed 5 fluid level therein and also for controlling a recirculation of the fluid within the apparatus through said recirculation pipe line in order to assure a suitable mechanical agitation both when raw fluid is being admitted and when little or no raw fluid is admitted.
8. A deactivator, embodying a fluid chamber, means for maintaining a vacuum in said chamber, means for delivering a fluid to the 10 chamber, means within the chamber for breaking up the delivered fluid, means for removing treated fluid from the chamber, a recirculation connection, and means for preserving a fixed fluid level within the chamber 15 and for controlling the recirculation of fluid through said connection.
9. In a liquid handling apparatus, a liquid receiving chamber, a supply connection therefor, an off-take connection to an external 20 load, liquid recirculating means, and means responsive to the rate of liquid off-take for regulating the amount of recirculation through said recirculating means.
10. In a liquid handling apparatus, a liquid receiving chamber, a liquid supply therefor, a liquid off-take to an external 25 load, liquid recirculating means, and means responsive to the rate of fluid supply to the chamber for regulating the amount of recirculation through said recirculating means.
11. In a liquid handling apparatus, a liquid receiving chamber, a liquid supply therefor, a liquid off-take to an external 30 load, liquid recirculating means, means responsive to the rate of liquid off-take for regulating the amount of recirculation through said means, and means for controlling the absolute pressure ratio of partial 35 pressures due to freed gases and the vapor of the liquid, respectively.
12. In a liquid handling apparatus, a liquid receiving chamber, a liquid supply therefor, a liquid off-take to an external 40
- load, liquid recirculating means, means responsive to the rate of liquid supply for regulating the amount of recirculation through said means, and means for controlling the absolute pressure ratio in said chamber of the partial pressures due to freed gases and the vapor of the liquid respectively. 45
13. In a liquid handling apparatus, a liquid receiving chamber, a liquid supply therefor, a liquid off-take to an external load, a recirculating connection between said off-take and supply, and means for regulating the amount of recirculation through said recirculating connection. 50
14. In a liquid handling apparatus, a liquid receiving chamber, a liquid supply therefor, a liquid off-take to an external load, a recirculating connection between said off-take and supply, and means for regulating the amount of recirculation through said recirculating connection, said last mentioned means being responsive to variations in the off-take to an external load. 55
15. In a liquid handling apparatus, a liquid receiving chamber, a liquid supply therefor, a liquid off-take to an external load, a recirculating connection between said off-take and supply, and means for regulating the amount of recirculation through said recirculating connection, said last mentioned means being responsive to variations in the rate of liquid supply. 60
16. In a liquid handling apparatus, a liquid receiving chamber, a liquid supply therefor, a liquid off-take to an external load, a recirculating connection between said off-take and supply, and means for regulating the amount of recirculation through said recirculating connection, said liquid chamber having means connected thereto for controlling the absolute pressure ratio of partial pressures due to freed gases and the vapor of the liquid respectively. 65

Signed at New York, in the county of New York and State of New York, this 14th day of Feb. A. D., 1923. 70

PERRY WEST.
